UNITED STATES PATENT OFFICE.

CARL SCHRAUBSTADTER, OF ST. LOUIS, MISSOURI.

DESIGN FOR A FONT OF TYPE.

45,894.

Specification for Design.

Patented June 2, 1914.

Application filed April 12, 1907. Serial No. 367,897. Term of patent 7 years.

To all whom it may concern:

Be it known that I, CARL SCHRAUBSTADTER, a citizen of the United States, and a resident of the city of St. Louis and State of Missouri, have invented a new, original, and ornamental Design for a Font of Type, of which the following is a specification.

My design consists in the features shown in the accompanying drawing which forms part of this specification.

I claim:

The ornamental design for a font of type shown.

CARL SCHRAUBSTADTER.

In the presence of—

JULIA B. MEGOWN,
G. A. PENNINGTON.

Copies of this patent may be obtained for five cents each, by addressing the "Commissioner of Patents, Washington, D. C."
